UNITED STATES PATENT OFFICE.

CLARE S. BRADLEY, OF BELOIT, WISCONSIN.

DESIGN FOR A DENTAL CROWN-DRIVER.

SPECIFICATION forming part of Design No. 32,617, dated May 1, 1900.

Application filed March 22, 1900. Serial No. 9,803. Term of patent 34 years.

To all whom it may concern:

Be it known that I, CLARE S. BRADLEY, a citizen of the United States, residing at Beloit, in the county of Rock and State of Wisconsin, have invented and produced a new and original Design for Dental Crown-Drivers, of which the following is a specification, reference being had to the drawings forming a part thereof.

- 10 (1) Figure 1 is an enlarged side view of a crown-driver embodying this design. Fig. 2 is an edge view of such instrument, and Figs. 3 and 4 are respectively lower and upper end views of the same.
- 15 (2) As shown in the drawings, the leading or material feature of my design consists in the form or configuration of a crown-driver, wherein A is the cylindrical stem of the in-

strument, and B the foot thereof. The foot B is formed integral with the stem A and extends to one side thereof. It has the flattened sides B¹, the square bottom B², and the curving edges B³, B⁴, and B⁵. The curves of these two latter edges join with and are continued in the outer surface of the cylindrical stem 20 A. The length of the bottom of the foot is about twice the diameter of the stem, and its plane is at an angle slightly greater than a right angle with the axial line of the stem A. 25

I claim as my invention—

The design for a dental crown-driver substantially as herein shown and described.

CLARE S. BRADLEY.
